UNITED STATES PATENT OFFICE.

AUSTIN N. RUITER, OF ABERCORN, QUEBEC, CANADA, ASSIGNOR TO
ORION NELSON ELKINS, OF NORTH TROY, VERMONT.

VEHICLE-AXLE CUTTER.

SPECIFICATION forming part of Letters Patent No. 299,854, dated June 3, 1884.

Application filed July 17, 1883. (Model.)

To all whom it may concern:

Be it known that I, AUSTIN N. RUITER, of 5
Abercorn, in the Province of Quebec and Do-
minion of Canada, have invented certain new
and useful Improvements in Vehicle-Axle Cut-
ters, of which the following is a full, clear, and
exact description.

This invention relates to apparatus or ma-
chines for cutting carriage or wagon axles.
10 Heretofore in cutting worn carriage-axles
it has been customary to turn the machine
around the axle while cutting it, to shorten
the arm between the collar of the axle and its
outer-threaded end portion, and afterward to
15 use an ordinary screw-plate to extend the
thread, and subsequently to cut off, by a file
or cold-chisel, or both, the surplus metal
from the axle. This not only involves a series
of operations attended with much difficulty,
20 time, and labor, but requires several separate
appliances to perform the work, and, owing
to the fact that the under side of the axle is
always the most worn, a machine or apparatus
which turns about a worn axle that presents
25 an uneven surface must necessarily make a
very irregular cut.

My invention consists in a machine, and in
certain combinations making up the same,
which, instead of revolving as an entirety
30 about the axle, is secured thereon, and which
combines in the one instrument both an axle-
cutter and a thread-cutter, capable of cutting
either a right or left hand thread, thus doing
away with the difficulties and objections here-
35 inbefore referred to.

Reference is to be had to the accompanying
drawings, forming a part of this specification,
in which similar letters of reference indicate
corresponding parts in all the figures.
40 Figure 1 represents a view in perspective of
a carriage or wagon axle cutting apparatus,
operating also as a thread-cutter, embodying
my invention; Fig. 2, a mainly sectional side
elevation of the same, omitting the handle by
45 which the device is operated; and Fig. 3, a
view in perspective of an axle-holding split
reducing-sleeve or bent plate used in the ap-
paratus.

A is the body part of the apparatus, having
50 a cylindrical reduced neck or tubular portion,

b, the aperture c in which extends through the
whole body part and is of sufficient capacity
to receive freely within it the largest carriage-
axle the apparatus is designed to operate upon.
The apparatus is slipped, by its hollow body 55
A and portion b, over the axle, and is secured
thereon by a split sleeve or bent plate, B, pro-
vided with a handle, b', introduced within the
aperture c, and by a set-screw, d, said plate
bearing on top of the axle, and the screw d be- 60
ing brought in contact with the under or worn
side of it, thus allowing the dies or cutters,
which are carried by a cutter-head, C, that ro-
tates around the stationary neck portion b, se-
cured on the axle, to revolve around the axle- 65
arm at a right angle and equidistant from the
center of it.

The sleeve B is of such a size that when sur-
rounding the smallest-sized axles to which it
is adapted a slot will be left between its split 70
sides for the passage of the binding-screw. If
larger-sized axles are to be operated upon, the
sleeve B will be expanded accordingly, leav-
ing a wider slot for the passage of said bind-
ing-screw, thus rendering the sleeve adapted 75
to be applied to different-sized axles. By the
cutter-head thus having a fixed cylindrical
bearing in concentric position with the axle-
arm, that irregularity of cut which attaches
to a machine that bodily turns around a worn 80
axle is avoided, and a regular cut is obtained,
no matter how much the axle or arm thereof
may be reduced by wear on its under side.

The cutter-head C is not only fitted so as to
be capable of being rotated around the portion 85
b of the fixed body part by means of a hand-
lever, D, but also of being longitudinally slid
thereon by a feed-lever, E, having its fulcrum
at e upon an arm, F, on the body A, and hav-
ing one of its ends made to enter an annular 90
groove, f, in the cutter-head C, and its other
end arranged to rest against a screw or ad-
justable stop, g, in the arm F, to limit the out-
ward movement of the cutter-head, which, by
reason of the groove f, may continue its rotary 95
motion while being moved up in or out on the
fixed tubular portion b. The axle being se-
cured by and arranged within the apparatus,
as described, a chisel or cutter, G, on the outer
end of the cutter-head C is brought in contact 100

with the end of the arm of the axle to be shortened, by means of an adjustable screw, *h*, and the feed-lever *E*, and the cutter-head rotated by the hand-lever *D*, to make the necessary reduction of the axle. The new extended screw-thread is then cut upon the axle by means of a cutter, *H*, on the cutter-head *C*, adjustable by a screw, *i*, and by a tracer, *I*, adjusted to follow in the old or original screw-thread, the cutter-head *C* being rotated as before, and the cutter *G* being withdrawn from action. This work having been completed, the cutter *G* is again brought into use to cut off so much of the end of the axle as is in excess of the length required. In this way or by these means all the necessary operations may be performed in the one apparatus in a simple, quick, and perfect manner.

Instead of using a hand-lever feed, as described, to move the cutter-head along the fixed tubular portion *b*, and which will be found better adapted to cutting the axles of wagons that have attached sand-boxes, an automatic feed may be employed.

25 I am aware that packing-plates surround-

ing an axle and provided with guide-pins have been adjusted by set-screws, and I therefore lay no claim to such construction.

Having thus described my invention, I claim as new and desire to secure by Letters Patent— 30

1. The combination, with the body *A*, having neck *b* and aperture *c*, and the rotary head *C*, provided with cutters *G H*, of a sleeve, *B*, having a longitudinal slit, and provided with a handle, *b'*, serving the double purpose of 35 limiting the inward movement of the sleeve and a means for operating the same, and screw *d*, passing through the slit of the sleeve and adapted to bear on the axle, substantially as described, and for the purpose set forth. 40

2. The combination, with the body *A* and head *C*, of the arm *E* on said body, the screw-stop *g*, and the feed-lever *E*, pivoted on a lateral stud of said arm and projecting into a groove of said head, as shown and described. 45

AUSTIN N. RUITER.
